US00D827346S

(12) **United States Design Patent** (10) **Patent No.:** **US D827,346 S**
(45) **Date of Patent:** **** Sep. 4, 2018**

(54) **TABLE**

(71) Applicant: **Pride Family Brands, Inc.**, Ft. Lauderdale, FL (US)

(72) Inventor: **Jamie Lowsky**, Aventura, FL (US)

(73) Assignee: **Pride Family Brands, Inc.**, Fort Lauderdale, FL (US)

(**) Term: **15 Years**

(21) Appl. No.: **29/563,693**

(22) Filed: **May 6, 2016**

(51) LOC (11) Cl. **06-03**

(52) U.S. Cl. USPC **D6/691.8**

(58) **Field of Classification Search**

USPC ... D6/349, 685-687, 690, 691, 691.2, 691.3, D6/691.5, 691.7, 691.8, 708
CPC .. A47B 7/00; A47B 7/02; A47B 13/00; A47B 13/003; A47B 13/02; A47B 13/023; A47B 13/04; A47B 13/06; A47B 13/08; A47B 13/081; A47B 13/12; A47B 21/00; A47B 2200/0011; A47B 2200/0015; A47B 2200/0016; A47B 2200/002

(57) **CLAIM**

The ornamental design for a table, as shown and described.

DESCRIPTION

FIG. 1 is a perspective view of my ornamental design; FIG. 2 is a rear side view of the ornamental design of FIG. 1;

FIG. 3 is a front side view of the ornamental design of FIG. 1;

FIG. 4 is a left side view of the ornamental design of FIG. 1;

FIG. 5 is a right side view of the ornamental design of FIG. 1;

FIG. 6 is a top plan view of the ornamental design of FIG. 1; and,

FIG. 7 is a bottom plan view of the ornamental design of FIG. 1.

The broken lines are shown for the purpose of illustrating a portion of the table that forms no part of the claimed design.

1 Claim, 6 Drawing Sheets
